ATTORNEY

UNITED STATES PATENT OFFICE.

WILLIAM WILSON, OF BROOKLYN, NEW YORK.

COMPRESSOR FOR REFRIGERATING UNITS.

Application filed September 24, 1924. Serial No. 739,625.

To all whom it may concern:

Be it known that I, WILLIAM WILSON, a citizen of the United States, residing at Brooklyn, in the county of Kings and State 5 of New York, have invented new and useful Improvements in Compressors for Refrigerating Units, of which the following is a specification.

This invention relates to a compressor for 10 a refrigerating machine such as would be especially adaptable for household purposes, embodying the elements of simplicity, safety, and automatic operation. The prime object of this invention, therefore, is to provide a 15 compact construction, with enclosed and protected mechanism, silent in operation, containing a self-lubricating system, and free from the danger of harmful and explosive gases. A further object is to provide 20 a simple method of assembly, so as to lower the cost of manufacture and enable ready inspection and easy replacement of parts.

To accomplish these objects there is employed 25 a hollow casing, preferably in the form of a pipe, sealed at both ends with an arrangement of flanged plates, this casing or pipe serving a double purpose, namely, as support for the compressor mechanism, 30 and as a receiver for the refrigerant. Contained and entirely enclosed within this casing is an electric motor directly connected with a system of gearing which actuates a reciprocating compressor piston, the motor 35 being lubricated by an independent wiping system, the gearing by lubricating grease contained within an inner gear casing, and the piston by an arrangement of oil reservoirs contained within one of the end flanges of 40 which the compressor cylinder is an integral part; the inner gear casing being provided with parallel extension bars serving both as a support for the motor and as an abutment against the flanged plates to prevent 45 vibration and rattling of the motor-gear arrangement; and the flanged plates being suitably supplied with inlet and outlet openings for the refrigerating fluid.

Referring to the drawings:

Figure 1 is a plan view, showing a part 50 section of the assembled compressor unit, with gear casing cover removed.

Figure 2 is a front elevation and Figure 3 a cross-sectional side elevation of the cylinder flange, showing oil reservoirs with 55 plugs.

Figure 4 is a plan view and Figure 5 an end elevation of the gear casing, showing extension bars and casing cover.

In the drawings, 1 is the casing containing the motor 2 connected through shaft 3 to gear 4 which motivates bevel gear 5. This bevel gear is attached to shaft 6 that rotates within bearing 7 forming part of the gear casing 8. Attached to the bevel 60 gear is connecting rod 9 which is connected to piston rod 10 and actuates piston 11. The compressor cylinder 12 within which the piston travels is an integral part of the flanged plate 13, and is lubricated 65 by the oil reservoirs 14 communicating with the cylinder by means of the oil channels 15, the reservoirs and channels being shown in Figures 2 and 3. These oil reservoirs are sealed by plugs 16 or by other suitable 70 means. The inlet piping for the refrigerant is connected to flanged plate 17 through opening 18; and the inlet into the compressor cylinder comprises the passages 19, the passage 20 running through the piston 75 rod and piston, and a suitable inlet valve situated at the head end 21 of the piston. The outlet valve 22 is situated within the exhaust chamber 23, within which exhaust valve spring 24 is contained, abutting 80 against the lug 25 of the cylinder head 26. The outlet passage 27 is connected with piping to the condenser. The gear casing 85 is provided with extension bars or skids 28, upon which the motor rests and is fastened 90 and secured with screws 29. The extension bars abut against the end plate at its inner surface 30, preventing vibration. The cover 31 for the gear casing is shown in Figures 95 4 and 5, and is suitably fastened thereto. Flanges 32 and 33 hold the end and cylinder flanges in place by means of bolting 34 and 35. The piston is provided with piston

rings 36. Gaskets 37 and 38 prevent leakage of the refrigerating gases into the atmosphere, and leather washers 39 and 40 constitute oil and grease seals. The cylinder head 5 plate is secured to the cylinder flange by studs 41.

The refrigerating fluid enters the unit through the opening 18, and passes around the spaces between casing 1 and the motor 10 2 and gear casing 8 into compartment 42, from which, on the suction stroke of the piston it enters the passages 19 and 20, passing through the open inlet valve situated at 21, and into the cylinder. On the 15 compression stroke, the inlet valve at 21 closes, the outlet valve 22 opens, and the fluid passes into the exhaust chamber 23, through the outlet passage 27, and into the condenser. The piston is automatically 20 lubricated by oil from the oil reservoirs 14, the oil channels 15 entering the cylinder 12 at such points that the terminals of these channels are always covered by the piston 11, regardless of its position, thus preventing 25 any of the oil from directly entering into the cylinder. The gears 4 and 5 are also self-lubricated by lubricating grease which fills the casing 8.

The cylinder flange 13 and the gear casing 8 are so designed that each serves several purposes. The flange contains, all within its body, the compressor cylinder, a complete lubricating system for the compressor piston, inlet ports, an exhaust chamber, outlet 35 ports for the refrigerating fluid, and serves as an end flange for casing 1. The gear casing 8 is designed to support the gears, to permit self-lubrication of these gears, and with the aid of the extension bars, serves as a 40 supporting base for the motor. The overall dimensions of this gear casing with its extension bars is exactly equal to the inside dimensions of the outer casing 1 from flange to flange, so that horizontal movement of the 45 motor-gear casing unit is prevented; hence the gear casing also functions as a means to eliminate vibration and allow silent operation.

As the compressor is entirely enclosed 50 within a sealed casing, there is no danger of any of the gases escaping into the atmosphere, as is often the case where the reciprocating part moves through an exposed stuffing box. Besides, the adaptability of this 55 unit to carbon dioxide, in particular, as the refrigerating fluid, or to other similar fluids, gives it an additional degree of safety not afforded by machines adapted for ammonia or other dangerous fluids.

60 Easy access to the exhaust chamber, exhaust valve, and cylinder is possible by removing the cylinder head 26 from the flange 13, so that inspection of those parts can be made in simple manner.

65 The motor and gear casing are so connect-

ed that they can be both withdrawn, as a unit, from the outer casing, by removing the cylinder flange 13, so that they can be inspected and parts replaced with great facility. The arrangement also permits of simple assembly, as the motor, gearing, gear casing, and piston can be independently assembled and then inserted into the outer casing 1 as a unit. This simple assembly helps greatly in reducing the labor element entering into the cost of manufacture.

What I claim is:

1. In a compressor for refrigerating units a flanged plate containing, integral with itself, a compressor cylinder, an exhaust chamber and outlet for the refrigerating fluid, and oil reservoirs communicating with the said cylinder through suitably situated oil channels for the automatic lubrication of the compressor cylinder.

2. In a compressor for refrigerating units a flanged plate containing, integral with itself, a compressor cylinder, an exhaust chamber and outlet for the refrigerating fluid, and oil reservoirs for the lubrication of the compressor piston, said compressor cylinder consisting of a cylindrical bore beginning at one face of said plate and extending into an enlarged concentrically arranged cylindrical bore terminating at the other face of said plate, said enlarged bore constituting the exhaust chamber and being suitably connected with an outlet for the refrigerant, and said oil reservoir comprising one or more suitably enclosed cylindrical compartments with axes 100 parallel to that of said compressor cylinder, and being connected with said compressor cylinder by suitable communicating channels.

3. In a compressor for refrigerating units, a hollow enclosed casing containing on its interior surface and integral with itself a bearing for gearing, and suitable openings for gear shafting and compressor piston, said casing being provided at one end with 110 two parallel extension bars serving as support for a motor and as an abutment for said casing to prevent its horizontal vibration, substantially as described.

4. A compressor for refrigerating units 115 comprising a hollow, tubular, open-ended casing suitably sealed at one end with an end plate containing an inlet opening for the refrigerating fluid; an electric motor; a system of bevel gearing with eccentric directly 120 connecting said motor with compressor piston; a gear casing substantially as described in claim 3, said gear casing containing said gearing and so set into said tubular casing that the parallel extension bars of said gear casing abut against said end plate and serve as a support for said motor; a compressor piston rod and piston containing a hollow open-ended passageway for the refrigerating fluid, said piston rod being connected to 125 130

an eccentric on said gearing to allow reciprocating motion of the piston; an inlet valve situated at the head end of said compressor piston; a flanged plate containing compressor cylinder, gas outlet and lubricating reservoir substantially as described in claim 3; an outlet valve with spring situated in the exhaust chamber of said flanged plate;

and a cylinder head plate, suitably secured and sealed to said flanged plate, and containing a hollow lug serving as an abutment for said exhaust valve spring, substantially as described. ¹⁰

In testimony whereof I affix my signature.

WILLIAM WILSON.
